UNITED STATES PATENT OFFICE.

MAX S. FINLEY, OF INDIANAPOLIS, INDIANA.

RADIORECEIVER.

Application filed June 6, 1922. Serial No. 566,230.

To all whom it may concern:

Be it known that I, MAX S. FINLEY, a citizen of the United States, residing at Indianapolis, in the county of Marion and State 5 of Indiana, have invented certain new and useful Improvements in Radioreceivers, of which the following is a specification.

This invention has reference to radio receivers, and its object is to provide an efficient and yet extremely simple and cheap 10 receiver for the purpose.

In accordance with the invention, there is provided a casing or housing composed of two sheets of insulating material joined at 15 the edges in face to face relation and carrying between them a primary coil and a secondary coil and numerous conducting terminals as well as means for holding the sheets from separating.

20 The coils are made of appropriate lengths of suitable wire for the purpose, in the form of coils, and the coils are connected at the ends to suitable terminals.

25 Certain of the terminals are utilized for an aerial and for the ground connections of the device and suitable others of the terminals receive the listening telephone.

The invention will be best understood from a consideration of the following detailed description taken in connection with 30 the accompanying drawings forming part of this specification, with the understanding that the invention is not confined to any strict conformity with the showing of the drawings, but may be changed and modified 35 so long as such changes and modifications mark no material departure from the salient features of the invention as expressed in the appended claims.

40 In the drawings:

Figure 1 is a face view of the radio receiver.

Fig. 2 is a rear view of the radio receiver.

45 Fig. 3 is a rear view of the radio receiver with the back section in most part removed.

Fig. 4 is a section on the line 4—4 of Fig. 3.

50 Figure 5 is a diagram of the connections. Referring to the drawings, there is shown a body member 1 composed of two cardboard sheets 2 and 3, respectively.

Between the sheets 2 and 3 there are located two coils, a primary 4, and a secondary 5.

At certain points, the two sheets or plates

have passed therethrough fastening devices 6—6, 7, 8, 9 and 10 which may consist of ordinary paper fasteners, usually of brass, in the form of staples readily obtainable 60 upon the market as well as being useful in most instances as electrical conductors. As shown in the drawings each fastener has a head and legs, which legs may be spread apart to secure the front and back sheets 65 2 and 3 together.

Through one of the sheets, near its center, are passed two more fasteners 11 and 12 spaced as shown.

While the first mentioned fasteners serve 70 to secure the sheets together, they also serve as terminals for the coils, and binding posts to which connections are made in setting up the device.

The primary coil has one end connected 75 to fastener 7, and the other end to fastener 8, as shown, and in setting up the instrument fastener 7, is connected to the aerial 13, and 8, is grounded.

The secondary coil has one terminal at 80 fastener 10, and the other at fastener 12, which fastener is passed through the sheet in opposite direction to 11, and has its legs about a galena crystal 14, on the outer surface of the sheet.

85 From fastener 9, a connection is run to and given a couple of turns about 11 and then through to the outer surface of the sheet, where its free end 15 provides a cat-whisker for locating the sensitive spot 90 upon the surface of the crystal when tuning in the set.

The head phones 17, are connected to fasteners 9 and 10.

For convenience in connecting up the 95 device, the surface of the upper sheet has marked thereon, beside each of the terminals, certain letters to indicate the proper connections to be made at the respective points. They are as follows, A at fastener 100 7, to indicate "aerial connection", G at fastener 8 to indicate "ground connection", and T—T at 9 and 10, to indicate "telephone connections."

As this device is not variable but tuned 105 to receive a wave length of about 360 meters, it is very easily set up, it only being necessary after the aerial, ground and phone connections have been made, to locate a sensitive spot upon the crystal with the cat-whisker, to receive signals.

With this device a simple, inexpensive,

self-tuned and efficient receiving set is obtained serving as an attractive advertising novelty, upon the front of which may be printed the donor's name with the advertising matter.

This receiver, because of its few parts, and extremely simple construction, may be constructed by unskilled labor, and at the same time is particularly effective, the only 10 manufactured part needed being the aerial and the head phones.

What is claimed is:—

1. In a radio receiver, a body member composed of spaced sheets of insulating material, primary and secondary wire coils between the sheets, and conducting terminals carried by the sheets and exposed with-

in and on one surface of the body member, said terminals being adapted to receive the aerial and ground wires, and conductors 20 for a receiving telephone.

2. In a radio receiver, two sheets of insulating material, primary and secondary coils constituting a transformer and housed one interior to the other between said insulating sheets, metal staples or other metal fasteners, traversing and joining the sheets together, other metal staples traversing one sheet and constituting terminals for the transformer, aerial and ground wires connected to the terminals. 25

In testimony whereof, I affix my signature hereto.

MAX S. FINLEY.
